CLAIM

The ornamental design for a pet bed, as shown and described.

DESCRIPTION

FIG. 1 is an isometric view of the pet bed of our invention;

FIG. 2 is a front elevational view thereof;

FIG. 3 is a back-elevational view thereof;

FIG. 4 is a first side-elevational view thereof;

FIG. 5 is a second side-elevational view thereof;

FIG. 6 is a top plan view thereof; and,

FIG. 7 is a bottom plan view thereof.

The dashed lines in FIGS. 1, 2, 3, 6, and 7 represent stitching.

FIG. 1

FIG. 2

FIG. 4

FIG. 3

FIG. 6

FIG. 5

FIG. 7
